APPARATUS FOR PRODUCING DISPLAYS BY ROTATING LUMINOUS BODIES

Joseph Otto Luthy, San Antonio, Tex.

Application December 23, 1940, Serial No. 371,324

4 Claims.

(Cl. 40—34)

This invention relates to apparatus in which displays are produced by rotating luminous bodies so as to result in various patterns or designs. The purpose of this invention is to provide such an apparatus that will automatically change the pattern of a display at fixed periods, with the apparatus arranging its own patterns so no one knows what the next display may be. This feature tends to hold the interest of the spectator, making the apparatus ideal for use in connection with advertising, as well as for the playing of games.

The following is a description of my invention. Figure 1 is a front elevation of the invention, partly in section. Figure 2 is a horizontal sectional view taken on line 2—2 in Figure 1, showing the mechanical part of the apparatus with a wiring diagram. Figure 3 is an enlarged view of the spring contact member 31 and its mounting.

1 in Figure 1 shows a front view of the housing or cabinet of the apparatus. 14 and 15 are the display plates, on which display tubes 18 and 19 are securely fastened with holdowns 24. 44, 45, 46, and 47 are the terminals of a fluorescent tubular lamp, shown as 48. In front of this lamp is mounted a transparent or partly transparent panel 49, on which a message or advertisement can be written, and which is hereafter called the advertising panel.

While one of the display tubes as shown in Figure 1 has the outline of a triangle and the other of a square, much greater changes in displays can be obtained with tubes bent along more irregular lines. The beauty of a display may also be enhanced by mounting two or more display tubes of different colors on a display plate, and this is especially true in larger sized apparatus; however, a tube or tubes should never overcrowd a display plate as this would cause too much fusion of colors while in motion.

To obtain more colors with the least number of tubes, different grades and colors of glass tubing can be used in making the individual tubes. For example, a tube to be filled with neon gas could be made partly from clear and partly from dark red or ruby glass tubing, which will result in two distinct shades of red. A tube filled with argon gas, made of clear and various shades of yellow glass tubing, will result in lighting effects of blue and different shades of green. A variation of colors can also be obtained from one tube by painting parts of it with different colors of transparent paint.

If part or parts of the display tubes are

painted with opaque paint very distinct changes of displays can be obtained from the same set of tubes.

As the beauty of these displays is based largely on stroboscopic action or effect, gaseous tubular lamps without any fluorescent coating give the best results. The reason the fluorescent coating is less satisfactory is that it retains part of its glow for a short period after the current has been cut off, thereby reducing, or in fact, almost annulling the stroboscopic effect obtained by the rapid interruption of light.

1 in Figure 2 shows the housing or cabinet of the apparatus; 2 the base or support for the rotating mechanism; 3 a bearing for the main driving shaft 4. This shaft is hollow and is provided on one end with pulley 5, and on its opposite end with flange 6 and threads 7. 8 shows the rotatable supporting member, carrying two display plates. In smaller units such as shown in the accompanying drawing this rotatable supporting member can be made of insulating material in the form of a strip of sufficient length and width to permit the mounting of the display plates, while for larger units it may be advisable to make it from metal, preferably aluminum for lightness, and it can be of various forms, such as a strip, disc, crossarm, or any other shape found most suitable.

30 The rotatable supporting member is provided at its center with a flange-type threaded bushing 9 which permits screwing it on to the threaded end of shaft 4. 10 shows a lock screw or bolt that can be tightened against shaft flange 6, thereby locking rotatable supporting member securely to shaft. 11 and 12 are hollow shafts, each provided on one end with a flange and on the other end with threads, nuts, and washers by which they can be securely fastened to the rotatable supporting member 8. On the inside of each of shafts 4, 11, and 12 is fastened a heavy-walled tube made of insulating material, shown as 13 13 13. The walls of these tubes must be of a thickness and quality of material that will assure dependable insulation between the shafts and the conducting parts placed therein.

14 and 15 are the display plates, which in smaller units can be made of an insulating material, while for larger units metal may be preferable. To reduce the weight of a display plate it could be perforated, or built in the form of a lattice, or if preferred, of wire netting stretched over a suitable frame. If the rotatable supporting member or the display plates are made of metal, all conducting parts leading to and from

spring contacts 31, 31a, and 31b are insulated from the metal.

These display plates are provided with flange bushings 16 and 17, which have bores to fit easily on their respective shafts 11 and 12, and are slightly longer than the thickness of the display plates to prevent the backs of these plates from rubbing against the nuts or washers of the shafts. As it is important that the display plates rotate as freely as possible on the shafts of the rotatable supporting member, the best results are obtained when the friction of these bearings is reduced as much as practicable. Various modifications of such bearings can be used without deviating from the spirit of this invention.

Another very important point is the balancing of a display plate so its weight is equally distributed, as otherwise a heavier part in such plate would have a tendency to control its position when in motion, thereby preventing change of patterns. If it is found that any part of a display plate is heavier than others, weight should be added where needed to obtain equal balance.

To reduce vibration in the apparatus, if two or more display plates are used they should be as nearly as possible of equal weight and placed uniformly on the rotatable supporting member. On the other hand, if only one display plate is used, sufficient weight should be added to the lighter end of the rotatable supporting member to give the whole a true balance.

18 is a display tube mounted on display plate 14, while 19 is a display tube mounted on display plate 15. 20 shows the connection from one terminal of tube 18 to bushing 16, while 21 shows the connection from the other terminal of said tube to spring contact 31. 22 connects one terminal of tube 19 to bushing 17, while 23 connects the other terminal of said tube to spring contact 31a. 24 shows the hold-downs for the display tubes. 25 shows an opening in display plate 14 to enable loosening or tightening of the lock screw or bolt 10.

26 shows an automatic flasher such as is used in connection with animated electric signs of the gaseous tube type. 27 is the electric motor for the operation of the automatic flasher, while 28, 29, and 30 are the switches controlled by the automatic flasher. The purpose of the automatic flasher is to close and open some of the electric circuits in the apparatus at fixed intervals. In spite of the continual duplicated action of the flasher it will result in continual changes of the display. This is made possible by taking advantage of the forces that are created by the whirling of the display plates and the rotatable supporting member at various speeds.

31, 31a, and 31b are spring contacts conducting the current from the rotating conducting plates on the inside of insulated shaft bushings 13, 13, 13. 32 and 33 are contact plates held under tension by spring 33 so as to form a solid electrical connection between contact spring 31b and shaft 12.

34 shows the electric motor which operates the rotating mechanism. 35 shows the motor pulley, and 36 the belt connecting it with driving pulley of the rotatable supporting member shaft. While the accompanying drawing shows the apparatus provided with a belt drive which I have selected on account of quietness of operation, a gear or silent chain drive could be used.

While the apparatus can be operated at various speeds it is preferable to operate it at the lowest speed required to give the desired results. In my

development work I have found that if the display does not exceed 20 inches in diameter, satisfactory results could be obtained with the rotatable supporting member whirling at a speed of approximately 250 revolutions per minute, while for a display of about 3 feet in diameter a speed of around 90 revolutions per minute was satisfactory. The speed at which the display plates should rotate is dependent upon the form of display desired, the type and form of display tubes, as well as the voltage and frequency of the tube current.

37 and 38 show leads from the electric supply line; 39 an adjustable resistance provided with an extra tap 39a. 40 is the step-up transformer to increase the line voltage to that required for the lighting of the display tubes. 41 is a high tension condenser connected in parallel with the secondary outlets of the transformer. To obtain the most satisfactory results from this condenser it should be of such capacity as to effect a noticeable change of frequency of the high tension current even at normal voltage, and a still further change of frequency with voltages below normal, which action generally results in a more pleasing appearance of the display.

42 is a choke or balancing coil inserted in the fluorescent tubular lamp circuit; 43 a low tension condenser also forming part of said circuit. 44, 45, 46, and 47 are the leads connecting to the fluorescent tubular lamp terminals of corresponding numbers as shown in Figure 1.

Figure 3 is an enlarged view of spring contact 31 and its mounting, which is a similar arrangement to that of the spring contact 31a. 31b is also a similar type of contact, forming connection between the insulated conductor in the driving shaft to one of the high tension terminals of the step-up transformer.

The electrical connection of the apparatus as shown in Figure 2 is such that when the current is turned on and with all three of the automatic flasher switches open it will result in the starting of the flasher motor 27, as well as the lighting of the display tubes 18 and 19 with reduced current due to the resistance inserted in the primary transformer circuit. The closing of flasher switch 28 will start the lighting of the fluorescent lamp 48, while the closing of flasher switch 29 will lower the resistance in the primary transformer circuit, thereby increasing the luminosity of the display tubes. The closing of flasher switch 30 will start the main motor 34.

While the automatic flasher may be regulated so the switches thereon will open and close at different periods and the adjustable resistance can be regulated to obtain the desired illumination of the display tubes during determined periods, I select for an example the following adjustment.

If the cycle of operation of the automatic flasher is to cover a period of 45 seconds the regulation of the resistance in the primary transformer circuit with flasher switch 29 open should be such as to reduce the current sufficiently to result in a noticeable reduction of luminosity in the display tubes, and with flasher switch 29 closed it should result in the increase of current to almost its normal strength. Too bright an illumination of the display tubes should be avoided, as it would only cause fusion instead of blending of colors when display plates are being whirled. The adjustment of the opening and closing of flasher switch 29 should be timed so that the period of reduced current in the dis-

play tube circuit is 25 seconds and that of increased current 20 seconds. The opening and closing of flasher switch 30, which controls the operation of motor 34, should be timed so that the flow of current in the motor circuit is interrupted for 4 seconds during every cycle of the flasher. In other words, if the length of a cycle of the flasher's operation is 45 seconds, the current to the motor 34 should be on 41 seconds and off 4 seconds. The timing of flasher switch 28 should be such that it is closed during the period of 4 seconds when flasher switch 30 is open.

After the adjustment of the resistance and automatic flasher has been made as above outlined, if the current is turned on at a period when flasher switches 28 and 29 are open and flasher switch 30 is closed, it will result in the starting of the flasher motor 27 and the main motor 34, as well as the lighting of the display tubes with reduced current.

While at the start of the whirling movement the display plates will have some tendency to rotate on their own axles this movement is rapidly checked with the increase of speed of the rotatable supporting member. When this speed has become uniform it will hold the display plates in alignment toward each other, thereby controlling the pattern of the display.

The reduced current in the display tube circuit with the action of the condenser will produce a pattern with somewhat sharp outline and much activity. If the speed of the whirling movement is kept uniform the pattern of the display will be retained with little or no change until, after 21 seconds, flasher switch 29 closes, thereby increasing the flow of current to the display tubes so as to cause a soft blending of colors. This effect also is retained with little or no change until, after 20 seconds, flasher switches 29 and 30 open and 28 closes. The closing of flasher switch 28 will start the lighting of fluorescent lamp 48, thereby illuminating the advertising panel 49. The opening of flasher switch 29 will again lower the current supply to the display tubes, while the opening of flasher switch 30 will cut off the current from main motor 34.

After the motor current has been cut off the momentum or force resulting from the whirling movement of the display plates and the rotatable supporting member will cause the whole to continue rotating, but with an immediate slackening of speed. As soon as this whirling movement diminishes nearly to its stopping point the display plates again will have a tendency to move around their own axles, which breaks up the pattern of the display. In the apparatus I have built the speed of the whirling movement of the display plates is such that it requires about 5 seconds for the rotatable supporting member to reach a dead stop after the current to the motor 34 has been cut off. Therefore, since flasher switch 30 closes within a period of 4 seconds, thereby again starting motor 34, the whirling movement of the display plates is resumed before it has actually reached its stopping point. The acceleration of the whirling movement of the display plates causes some movement of them around their own axles, until the speed of the whirling movement has become uniform and sufficient to again hold them in alignment toward each other, which action results in the forming of a new

pattern of display that in practically every case is different from the one preceding.

The moment flasher switch 30 closes, flasher switch 28 opens, thereby cutting off the current in the fluorescent lamp circuit. This completes a cycle of the automatic flasher's action, and while its succeeding cycles will consist of the same action, even a slight movement of the display plates during each period of reduction and acceleration of speed of the whirling movement will result in a change of pattern. From the above explanation it can be seen that it would be practically impossible to foretell what the next pattern will be, which feature holds the interest of spectators.

While the momentary reduction of speed in the whirling movement of the display plates and the acceleration of it is sufficient to effect a change of display, in some cases it may be preferable to stop the whirling movement entirely and start it again. This would be especially true if the apparatus be used for the playing of games in which the display plates could be provided with characters or symbols that would form patterns while in motion but would be legible when stopped, their position indicating winning or losing.

On the other hand, if the apparatus is used as an attraction or for advertising purposes, I believe the momentary reduction of speed in whirling the display plates to change the pattern thereon would be preferable. The reason for this is that the change of display takes place so quickly that it is practically impossible to discern the real movements of the display plates before a new pattern is created, which makes the action of the apparatus more mystifying and interesting.

If it is desired to bring the whirling movement of the display plates to a standstill during each cycle of the flasher all that is necessary is to prolong the stopping period of the motor 34. If it is desired to change the display pattern more often, all that is required is either to increase the speed of the control disc shaft of the flasher, or use flasher control discs having provisions for more changes. This also holds good as to the time period for lighting the fluorescent lamp, so that if the apparatus is used for advertising purposes it can be adjusted to illuminate the advertising panel as often and for as long as desired. If a lower priced apparatus should be desired it could be built without the automatic flasher. In such case each time the apparatus is stopped and started again it would result in a change of the display pattern.

While the accompanying drawing and foregoing specification show and describe an apparatus in which two display plates are used, an apparatus could be built with one, three, four, or more display plates. If only one display plate is used its axle should be mounted a distance from the axle of the rotatable supporting member so the stopping and starting of its whirling movement will result in a change of display.

While the accompanying drawing and foregoing specification show the use of gaseous tubes as the luminous bodies of display, incandescent or glow lamps of various types, colors, and forms could be used instead. As incandescent or glow lamps operate on a much lower current voltage but an increased ampere rate it would require an increase in size of the current conducting parts in the lighting circuit; however, as in such

in a circuit the insulating parts could be greatly reduced, the working mechanism of the apparatus would require little if any more space than one built for the use of gaseous tubes.

If desired, high frequency current could be used for illuminating the gaseous display tubes, which would have the advantage of simplifying the apparatus by eliminating the necessity of spring contacts as well as most insulating requirements. In using high frequency current, all that would be required would be to connect one terminal of the high frequency coil to the ground and the other through the bearing of the rotatable supporting member to the bearing of the display plate or plates and from there to one terminal of each display tube.

While in the description of this invention the advertising panel is part of the apparatus, if preferred, this panel could be some distance away, yet controlled by the automatic flasher in the apparatus. The flasher switches controlling the illumination of such panel could also be made to control two or more panels located at different places. The automatic flasher could also be provided with two or more switches for the controlling of panel lamps, so it would result, during each cycle of the flasher, in the illumination of different panels, either multiple or alternate, each for a determined period of time. In such arrangement the use of different colored lamps in the various panels would add to its attractiveness.

All of the foregoing suggestions for modification of the apparatus could be carried out without departing in the least from the spirit of this invention.

What I claim as new and patentable is:

1. A display apparatus including a rotary main member, display means, means to movably mount the display means on the main member for free and uncontrolled rotary movements independently of the main member, means to drive the

main member only thereby to rotate same and through its rotation to rotate the display means solely by the force derived by and from the starting and stopping of the main member,

5 means for effecting said starting and stopping of the main member whereby the rotation of the display means is uncontrolled save by such force as it derives from the starting and stopping of the main member, and said display means having its weight equally distributed to provide equal balance thereof, whereby the pattern of the display means is successively changed, during said starting and stopping of the main member.

2. A display apparatus in accordance with claim 1, wherein there is a plurality of display means.

3. A display apparatus in accordance with claim 1, wherein the display means is of circular outline and has the axis of rotation at the center thereof.

4. A display apparatus including a rotary main member, display means, means to movably mount the display means on the main member for free and uncontrolled rotary movements independently of the main member, means to drive the main member only thereby to rotate same and through its rotation to rotate the display means solely by the force derived by and during the acceleration and deceleration of the main member, means for effecting said acceleration and deceleration of the main member whereby the rotation of the display means is uncontrolled save by such force as it derives from the acceleration and deceleration of the main member, and said display means having its weight equally distributed to provide equal balance thereof, whereby the pattern of the display means is successively changed, during said acceleration and deceleration of the main member.

JOSEPH OTTO LUTHY.
